UNITED STATES PATENT OFFICE.

OTTO H. ESCHHOLZ, OF PITTSBURGH, PENNSYLVANIA, ASSIGNOR TO WESTINGHOUSE ELECTRIC & MANUFACTURING COMPANY, A CORPORATION OF PENNSYLVANIA.

ARCING CONTACT.

Application filed October 8, 1923. Serial No. 522,627.

My invention relates to circuit interrupters and particularly to means for effecting the separation of two relatively movable contact members and extinguishing arcs that may be formed therebetween.

5 The object of my invention is to provide a pair of relatively movable contact members with means for preventing the reignition of an electric arc after it has been extinguished.

10 Another object of my invention is to so arrange the relatively movable contact members that magnetic forces are set up therein to act as a blowout field for arcs that may be formed therebetween.

15 Another object of my invention is to provide contact members in which the rating may be increased, for a given character of distress, by maintaining a comparatively short arc length with a maximum arc-terminal separation.

20 A further object of my invention is to provide relatively movable contact members so designed that an arc formed between two vertically disposed arcing tips will assume 25 a horizontal position.

It is also an object of my invention to provide contact members so arranged that the gas generated by an arc at either contact member escapes at a desired angle to the direction of the arc stream, thereby facilitating 30 the removal of the gas generated at the contacts and in the arc stream, as well as increasing the dielectric strength of the medium between the arcing tips against the 35 re-ignition of the arc.

I have found, in practice, that the oil-circuit-breaker distress on rupturing alternating-current circuits is a function of the 40 arc energy. This is dependent upon the magnitudes of the short-circuit current and the arc voltage, the latter being subject to control by adequate design of arcing tips. Circuit-breaker rating may be increased for a given character of distress by maintaining 45 a low arc voltage or a comparatively short-arc-terminal separation.

In my invention, the dielectric strength of the medium surrounding the arcing tips during the arc-rupture period is increased 50 by the removal of the arc gases from the vicinity of the arcing tips.

Figure 1 illustrates, in side elevation, the closed position of a pair of arcing tips designed in accordance with my invention.

55 Fig. 2 illustrates, in side elevation, the

open position of the arcing tips, and the progressive positions assumed by the arc stream are shown by means of dotted lines.

Fig. 3 illustrates, in side elevation, a portion of a contact member provided with arcing tips constructed in accordance with my invention.

Fig. 4 is a cross section of the movable arcing tip on section line A—A of Fig. 2.

I provide a pair of relatively movable 65 arcing tip members 1 and 2, member 1 being placed above member 2. Member 1 comprises an approximately straight horizontal portion 3, and a curved portion 4 that terminates in an enlarged arcing tip 5. 70

Contact member 2 comprises an approximately straight horizontal contact portion 6, curved portion 7 and an enlarged arcing tip 8. The radius of curvature of the curved portion 7 is materially greater than 75 that of the portion 4. The arcing tips 5 and 8 may be of solid construction or they may be made hollow, as desired.

It is to be noted that the extremities of the arcing tips 5 and 8 lie in approximately 80 the same horizontal plane. For low current values, the members 1 and 2 may be cut off at B (Fig. 2).

As shown in Fig. 4, the cross section of movable member 2 is designed to present 85 a stream-line curve to the liquid, thereby reducing the resistance of the liquid to movement of said member.

Upon separation of the contact portions 4 and 6, an arc is formed, as at A (Fig. 2). 90 The arc stream moves outwardly on the arcing tips 5 and 8 because of the repulsive forces of the magnetic fields produced by the current traversing the arc stream and contact members. The progressive positions of the arc stream are shown by the dotted line positions in Fig. 2.

The position of the arc stream, upon its formation, is in a vertical plane but, during the progressive movement of the arc stream 100 along the curved portions 3 and 7, the plane becomes substantially horizontal when it reaches the arcing tips 5 and 8. During this movement, the length of the arc stream increases somewhat and the magnetic impelling 105 or blowout force decreases. When the arc stream reaches the enlarged portions of the arcing tips 5 and 8, it ceases to increase in length because of the blowout effects, although it may be somewhat extended by 110

convection currents and further arc-terminal separation. Because of the character of the arc-stream path, a relatively short arc-stream length has been maintained, hence, a low arc voltage, with the accompanying development of low arc energy, obtains.

The contour of the arcing-tips may be such as to provide relatively large masses, thereby facilitating the cooling of the arc terminals, and, hence, preventing arc re-establishment. It is obvious, that, under such conditions, a reduction of potential gradient may be secured between the arcing tips, thereby preventing breakdown of the dielectric separating them after the current has reached zero.

Because of the horizontal position of the arc stream, the arc gases rise upwardly from each arcing tip in a direction at a desired angle to the arc stream. The diversion of the gas from the path of the arc stream materially increases the strength of the dielectric between the contact members. Arc gases, when allowed to travel from one terminal to the other, as when the arc terminals are in substantially the same vertical plane, facilitate the maintenance of the arc stream.

By reference to Fig. 3, it may be noted that contact members 11 and 12 become separated slightly in advance of the separation of the arcing tips because of the action of spring 13. Contact members 11 and 12 also interrupt the greater portion of the electrical current, members 5 and 8 serving as arcing tips for protecting the main contact members. A spring 14 may be employed to support the member 2. The positions of the arcing tip members with relation to the contact members 11 and 12 may be varied as desired, so long as the extremities of the arcing tips are in approximately the same horizontal plane.

By combining there several advantageous features in my circuit interrupter, I have invented a device in which a relatively constant arc length of some predetermined minimum value is maintained with a maximum arc-terminal separation.

Various modifications and changes may be made herein, without departing from the spirit and scope of the invention, as defined by the accompanying claims.

I claim as my invention:

1. A method of extinguishing an electric arc which consists in causing an arc stream to finally assume a substantially horizontal position from an initial vertical position and thus causing the gases generated by the electric arc to escape from the path of the arc stream at substantially a right angle.

2. A circuit interrupter comprising a pair of parallel contact members and a curved arcing-tip member for, and extending at an angle to, each contact member, said arcing tips having different radii of curvature and the extremities of said arcing tips being in approximately the same horizontal plane.

3. A circuit interrupter comprising a pair of parallel contact members and a curved arcing-tip member for, and extending at an angle to, each contact member, said arcing-tip members having different radii of curvature and the extremities of the arcing tips being in approximately the same horizontal plane, the cross-sectional area of the arcing-tip members increasing outwardly from the contact members, whereby a large surface area is had at the extremities of the arcing tips resulting in a uniform potential gradient between said tips.

4. A circuit interrupter comprising a pair of parallel contact members and a curved arcing-tip member secured at an angle to each contact member, said arcing tip members having different radii of curvature and the extremities of the arcing tips being in approximately the same horizontal plane, the cross-sectional area of the arcing-tip members increasing outwardly from the contact members, whereby a large surface area and a large mass of material is had at the end of each arcing tip.

5. In a circuit breaker, the combination with separable main, contact members, of curved arcing tips of different lengths projecting laterally from said members to a spaced and approximately parallel relation in which their extremities are in a plane substantially parallel to the contact surfaces of the main members when in their circuit-closing positions.

6. A circuit breaker comprising separable main contact members provided with laterally projecting curved arcing-tips of different lengths having enlarged outer ends, the extremities of which are spaced apart in a plane substantially parallel to the contact faces of the main members when in their circuit-closing positions.

7. A circuit breaker comprising separable main contact members provided with laterally projecting curved arcing tips of different lengths, the extremities of which are spaced apart in a plane substantially parallel to the contact faces of the main members when in their circuit-closing positions.

In testimony whereof, I have hereunto subscribed my name this second day of October, 1922.

OTTO H. ESCHHOLZ.
